UNITED STATES PATENT OFFICE

WALTER EVERETT MOLINS, OF DEPTFORD, LONDON, ENGLAND

CIGARETTE MACHINERY

Application filed June 13, 1927, Serial No. 198,634, and in Great Britain February 11, 1927.

This invention is for improvements in or relating to cigarette machinery and more particularly to a device for severing an axially moving rod into lengths of the type wherein the cutting blade is arranged to sweep, by an arcual movement, across the path of the rod and simultaneously travel with the rod at the axial speed thereof.

The present invention consists of a device for severing an axially moving rod into lengths of the type referred to, wherein means dependent upon the arcual movement of the blade is operable to ensure that the cutting edge of the blade sweeps through an arcual path of a constant radius in its movement across the path of the moving rod.

Further, the present invention consists of a device for severing an axially moving rod into lengths of the type referred to wherein means dependent upon the rotational movement of the blade is operable automatically to feed forward the blade so as to always maintain the cutting edge of the same at a predetermined radius from the rotational axis of the blade.

The invention is more particularly described with reference to the accompanying drawings, in which:

Fig. 1 is a view of one pair of knife carrying links constructed, arranged and adapted to operate in the manner described in specification No. 248,415, with the subject matter of the present application applied thereto.

Fig. 2 is a part plan view of the device illustrated in Fig. 1.

Fig. 3 is a sectional end view on the line *a—b* of the device illustrated in Fig. 2.

Fig. 4 is a plan view of the stop wheel illustrated in Fig. 1, and

Fig. 5 is an enlarged section on the line *c—d* of the stop wheel illustrated in Fig. 1.

Referring to the drawings, the invention shown is applied to a cutting device adapted to sever an axially moving rod into lengths wherein the cutting blade is arranged periodically to intersect the path of the cigarette rod and simultaneously move with the rod during the period of intersection. A detachable segmental cutting blade 1 mounted upon rotatable parallel link mechanism 2 is

according to the present invention clamped to the link 3 which is arranged parallel to the axis of the axially fixed rotatable shaft 4, in such a manner as to permit the same to move radially under the centrifugal force exerted upon the blade during the rotation of the said mechanism.

The clamping device which holds the blade in position upon the said link, comprises a plate 5 preferably made of aluminium through which a bolt 6 is arranged to extend. The bolt 6 is adapted to receive a sleeve 7 which is provided with an enlarged head 8 which is adapted to sit in a countersunk portion of the plate 5 and lie flush with the upper surface thereof.

Arranged to fit over the sleeve 7 is a plate 9 preferably formed of steel against which the bifurcated knife 1 is arranged to bear. Arranged to rest on the top of the knife is a second steel plate 10 and the two plates and blade are held in position by an upper aluminium plate 11 which is provided with overlapping edges 12 adapted to hold the plates 9 and 10 and the knife 1 in position.

Arranged to extend over the bolt 6 so as to rest upon the upper face of the sleeve 7 is a spider shape spring 13 provided with three adjusting screws 14 and the plate is clamped upon the upper surface of the sleeve 7 by means of a nut 15.

When the plate is fixed in position, the adjusting screws 14 are clamped down upon the plate 11 until the blade 1 is held within the holder in such a manner as to permit the same to be fed in a radial direction by an extremely small amount (for example one-thousandth of an inch in each ten revolutions) as the parallel link mechanism 2 rotates about the shaft 4. The blade 1 in this manner is continuously fed forward in a radial direction, and in order to prevent the same from being fed too far beyond the rotary path of the parallel link mechanism, the blade is arranged to engage with a grooved stop wheel 16 which is carried upon a spindle 17 and the bevelled faces 18 of the wheel are arranged to terminate in a slot 19 which is arranged to receive the cutting edge of the blade and permit the bevelled edge of

the blade to bear on either side of the wheel so as to limit the radial displacement of the blade relatively to the holder.

In this manner the wheel periodically engages with the blade and maintains the cutting blade at a predetermined distance from the rotational axis of the parallel link mechanism, thus ensuring that as the cutting edge of the knife is ground away by the automatic grinders, the blade is automatically fed forward, thus obviating the necessity of the cutting mechanism being stopped so as to adjust the position of the blade from time to time.

15 It will be appreciated that the device which forms the subject matter of the present invention may be readily applied to any type of cutting mechanism wherein the cutting blade is subjected to centrifugal action, 20 whether the path of the cutting blade be a complete circle or an arcual displacement, or whether the blade is fixed upon a rotatable holder or is adapted to revolve relatively thereto. Various alterations in the 25 constructional details of the device may be made within the spirit and scope of the invention as defined in the accompanying claims.

What I claim as my invention and desire to secure by Letters Patent is:—

30 1. In a device of the class described having a rotatable support, the combination with a cutting element mounted on said support, of retaining means on said support frictionally engaging said cutting element 35 whereby said element is automatically movable with relation to said support by centrifugal action.

2. In a device of the class described having a rotatable support, the combination with 40 cutting means mounted thereon for movement outwardly from the axis of said support, of a device in engagement with said cutting means for retarding outwardly movement thereof, whereby said cutting means is 45 gradually fed outwardly by the action of centrifugal force.

3. In a device of the class described having a rotatable element, the combination with 50 cutting means mounted thereon for movement outwardly from the axis of said element, of a device in engagement with said cutting means for retarding outward movement thereof, whereby said cutting means is gradually fed outwardly by the action of 55 centrifugal force, and a member for engagement with said cutting means to positively limit outward movement thereof.

4. In a device of the class described having a rotatable element, the combination with 60 cutting means mounted thereon for movement outwardly from the axis of said element, of a device in engagement with said cutting means for retarding outward movement thereof, whereby said cutting means is 65 gradually fed outwardly by the action of

centrifugal force, a fixed support, and a member mounted thereon for periodically engaging said cutting means to positively limit outward movement thereof.

5. In a device of the class described having 70 a rotatable element, the combination with means provided with a cutting edge mounted thereon for movement outwardly of the axis of said element, of a device mounted on said element and engaging said means for retarding outward movement thereof, and a member for engagement with said cutting edge to limit the outward movement of said means.

6. In a device for severing an axially moving rod into lengths having a cutting blade holder which is movable transversely of the path of the rod and is operable to travel with the rod during such transverse movement, the combination with a cutting blade carried by said holder, means for yieldingly retaining said blade against forward feeding movement with respect to said holder, and means for restricting the amount of forward feeding movement of the blade.

7. In a device for severing an axially moving rod into lengths having a cutting blade holder which is movable transversely of the path of the rod and is operable to travel with the rod during such transverse movement, the combination with a cutting blade carried by said holder, means for yieldingly retaining said blade against forward feeding movement during rotation of said holder, and means for restricting the amount of forward feeding movement of the blade.

8. In a device for severing an axially moving rod into lengths having a cutting blade holder which is movable transversely of the path of the rod and is operable to travel with the rod during such transverse movement, the combination with a cutting blade carried by said holder, means for yieldingly retaining said blade against forward feeding movement during rotation of said holder, and means arranged in the path of movement of the blade for maintaining the cutting edge thereof at a constant distance from the rotational axis of the holder.

9. In a device for severing an axially moving rod into lengths having a cutting blade holder which is movable transversely of the path of the rod and is operable to travel with the rod during such transverse movement, the combination with a cutting blade carried by said holder, a spring controlled element for retarding radial movement of said blade during rotational movement of the holder, and a stop mounted in the path of the blade for limiting radial movement thereof.

In testimony whereof I hereunto affix my signature.

WALTER EVERETT MOLINS.
